UNITED STATES PATENT OFFICE.

HAVEN COOK PERHAM, OF LOWELL, MASSACHUSETTS, ASSIGNOR TO KITSON MACHINE SHOP, OF LOWELL, MASSACHUSETTS, A CORPORATION OF MASSACHUSETTS.

CONDENSER-LAP MACHINE.

1,034,827.

Specification of Letters Patent.

Patented Aug. 6, 1912.

Application filed August 19, 1908. Serial No. 449,348.

To all whom it may concern:

Be it known that I, HAVEN COOK PERHAM, of Lowell, in the county of Middlesex and State of Massachusetts, have invented certain new and useful Improvements in Condenser-Lap Machines, of which the following description, with the accompanying drawings, is a specification.

Like letters on the drawings denote like parts.

This invention is an improvement in condenser-lap machines and particularly in means for preventing the splitting of laps as they unroll upon the aprons of succeeding machines, such as other condenser-lap machines and carding-engines.

It relates to improvements in means for advancing-and-compacting the fibrous material in combination with fiber-rearranging means whereby certain fibers are intermixed and interwoven with other fibers before the lap is rolled and the splitting of the lap thereafter prevented. Its objects are: first, to provide a more efficient form for the forward-terminal portion of the fiber-rearranging means; second, to arrange the said portion and, especially, its fiber-rearranging elements in more efficient relation to the fiber advancing-and-compacting surfaces with which they coact; third, to improve the means for the attachment of the fiber-rearranging means; and, fourth, to provide attachments for condenser-lap machines such as can be manufactured and sold independently of the said machines and applied thereto in a mill that is far from any well-equipped machine shop and which comprise fiber-rearranging means. These objects are attained by the mechanism that is illustrated in the accompanying drawing, in which:

Figure 1 is a diagrammatic representation of a portion of a condenser-lap machine. Fig. 2 represents a detail in elevation. Fig. 3 represents in plan two of the teeth shown in Fig. 2. Figs. 4, 5, and 6 are cross-sections taken on lines 4—4, 5—5, and 6—6 respectively of Fig. 2. Figs. 7, 8, and 9 represent a modification. Figs. 10 and 11 are cross-sections taken on lines 10—10 and 11—11

respectively of Fig. 9. Fig. 12 represents another modification. Fig. 13 represents another location for the attachment of the teeth. Fig. 14 is a longitudinal-section along the axis of a tooth not yet sprung into its operative position.

In Fig. 1, 1 represents the forward end of a "trough-bottom" that is more specifically called a "screen" or a "grid." It is the bottom of the "trough" or "trunk," 60 through which the lap-forming-materials pass to the "condenser-cages" 2 2. The "trunk-cover" is represented by 3. The arrow in the trunk indicates the general direction of the motion of such materials. The 65 typical shape of the surface of the previously deposited mass of such materials is represented in cross-section, by the line 4 4 4, although the actual shape of such cross-section varies considerably from time to 70 time. Within the trunk and approaching the surface represented by 4 4 4, are shown flying tufts or fragments of such materials. Ordinarily, the parts of such tufts adhere together better than such whole tufts or 75 fragments adhere to one another. As such materials pass the draw-rolls 5 5 over the draw-plate 6 they are called a "sheet." The sheet is compacted by the calender-rolls 7 7 7 7, and finally is wound by the winding- 80 drums 8 8 into a lap 9.

The surface represented by 4 4 4 is one of comparatively easy splitting. In the sheet, it becomes substantially V-shaped with its angle in advance and near the center of the 85 sheet and with its other extremities in the surfaces of the sheet. In the lap, the outer surface splits more easily than the inner one. Laps that contain much waste composed of tufts of straight parallel fibers, 90 split very easily between or through such tufts and easily fall apart. By my invention, I disarrange such parallelism and confusedly intermix and interweave fibers of different tufts by dragging forward some 95 fibers or parts of fibers and by detaining others or parts of others. I prefer that such rearrangement of the fibers shall occur throughout the thickness of the lap, that it shall be most effective in a series of narrow 100

and parallel strips of the sheet, and, especially so, in the outside surface of the rolled lap. I make this rearrangement more permanent by severely compacting the materials immediately after the rearrangement and before the stresses that have been produced during the rearrangement within the elastic mass of the materials have had opportunity to return the rearranged fibers to their original positions to any important extent.

In my improvements I utilize any usual co-acting fiber-advancing-and-compacting surfaces preferably the surfaces of the upper pair of calender-rolls. I particularly utilize the parts of such surfaces where they bite the materials and another part of the surface of one of them, preferably the lower surface of the upper calender-roll. Preferably, I oppose to the said lower surface a series of teeth or projections situated but a short distance apart in a line parallel to the axes of the calender-rolls and extending entirely across the machine. Preferably: the form of the forward-terminal portion of each such tooth is that of a straight piece of round spring-steel wire, having a diameter that is small as compared with the distance between the centers of the teeth; the tooth is directed toward the lower surface of the upper calender-roll at a large acute angle therewith; the width of the entire tooth and therefore of its back is narrow as compared with the width of the space between the centers of the teeth; the end of a tooth has the rounded shape which a tooth takes on if, when new, it had a flat end at right angles with the axis of the forward terminal part of the tooth and a sharp edge at the juncture of the end with the sides and back of the tooth, but which has lost its sharp edge by continued wear. When the sheet is between the end of the tooth and the said lower surface, the end of the tooth is in close proximity to the said lower surface and is near to the fibers that are in the bite of the said pair of calender-rolls; and there is a space between the ends of the teeth and the bite of the rolls. It follows from this construction: that a series of parallel and narrow strips of the sheet are gradually condensed as they pass along the forward-terminal portions of the teeth and the lower surface of the roll; that between the lower surface of the advancing roll and the end of each stationary tooth the sheet is severely compressed; that the action of the rolls at their bite tends to drag the whole sheet forward; that the frictional contact of the lower surface of the advancing roll with the upper surface of the sheet, opposite to the ends of the teeth, tends to drag the sheet forward; that the frictional contact of the ends of the stationary teeth with portions

of the lower surface of the sheet tends to detain the sheet; that portions of the sheet, portions of the tufts of which it is composed, and portions of its fibers will be more, or less dragged forward or detained and the fibers of the sheet rearranged; and, that the nearness of the ends of the teeth to the fibers that are held in the bite of the rolls tends to prevent the detaining teeth from tearing holes in the sheet. As the sheet passes out from between the teeth and the roll and before it passes into the bite of the rolls, it expands considerably. This expansion aids in the rearrangement of the fibers. The compression of the materials in the bite of the rolls tends to make the rearrangement permanent.

I prefer to make the end-surface of a tooth small in area and the back of a tooth narrow relatively to the width of the sheet between teeth, because the force required to press such teeth against the co-acting surface is less than if the end-surfaces had a larger area and the backs were wider, and because such teeth sufficiently rearrange the fibers. Experience has shown that, in order to satisfactorily effect the desired rearrangement of the fibers, the pressure with which the sheet is squeezed between two bodies, one of which advances relatively to the other, must be severe, and that satisfactory results can be had if the severe pressure is distinctly localized so as to affect only a very small proportion of the area of the sheet at a time. As the sheet squeezes into the bite between the roll and the end of a tooth it can be subjected to a severe pressure only when the tooth is designed to severely resist the expansion of the sheet in the bite. To adapt the tooth to perform this function, it has been constructed as a straight strut from its end at the bite to the point where it leaves its support, it has been given a direction nearly radial to the surface of the roll; and the severity of the pressure of the tooth upon the sheet has been distinctly localized and intensified by giving its end a small area relatively to that of the sheet and such a shape that a point of its end comes nearer to the lower surface of the roll than any other point of the tooth. This particular point co-acts with the roll to bite the sheet with greater severity than any other point of the tooth and is the most efficient point of the tooth for the purpose of rearranging the fibers. In order that the advancing sheet may not be torn but directed into the bite, and in order that their ends may be near to the fibers that are held in the bite of the calender-rolls, the teeth are not precisely radial to the surface of the roll at the bite.

In my invention, the teeth are so presented, opposed, and arranged relatively to the lower surface of the roll that the parts

of the sheet which touch and slide upon their extreme forward-terminal portions pass: first, upward-and-forward; second, across the ends of the teeth; and third, 5 downward-and-backward as the sheet expands. Thus, these parts of the sheet change their direction through about 180° in passing the ends of the teeth. The larger the angle through which the sheet changes 10 its direction as it slides upon the extreme forward-terminal portions of the teeth, the more efficiently the teeth act as detainers of parts of the sheet.

I prefer that the teeth shall project from 15 the draw-plate 6, although they may project from the screen 1, as shown in Fig. 13, or other support. The teeth fastened to their support may constitute an attachment to be manufactured and sold separately 20 from the machine. Preferably, I fasten each tooth to the forward end of the draw-plate separately from and independently of any other tooth. Each separate tooth with the means for attaching it to the support 25 may constitute an attachment to be made and sold separately from the support.

In Figs. 1, 2, 3, 4, 5, 6, and 14 there is represented the form of tooth 10 and the means for attaching it to the support which 30 I prefer to use in old condenser-lap machines which operate upon a quite heterogeneous mass of lap-forming-materials and especially so when the machines are situated at a considerable distance from any well 35 equipped machine-shop. The draw-plates 6 of such machines can easily be removed from the machines and a series of small holes 12 drilled therein. Each hole should be of such size that the wire 10 will fit 40 easily without unnecessary looseness therein and all of the holes should preferably be situated in one straight line parallel to the center-lines of the calender rolls 777. The means for attaching the tooth to the draw- 45 plate or other support, which for cheapness I prefer to use in this case, is the combination of: an integral extension of the sprung-wire tooth having the same cross-section as the tooth, having a threaded part adapted 50 to pass through a hole 14 in a washer 11 and a hole 12 in the support, and having a portion at an angle with the threaded part adapted to be drawn by a nut into a groove 55 13 in the washer; a washer 11 having a hole 14 therethrough, having a V-shaped groove 13 radiating from the hole 14, and having three feet 15 15 15 radially distant from the hole for contact with the support; and, a nut for the threaded part. The support of 60 a tooth upon a draw-plate will be the more stable because of the feet 15 15 15. In the preferred form of my invention, the two feet that are farthest removed from the hole through the draw-plate are spread 65 apart to give increased stability and in the

process of springing the extension of the preferred form of tooth into its permanent position, as will be explained below, considerable pressure is applied to force both of these feet hard against the draw-plate and 70 to prevent them from slipping thereupon. Radially, they are quite distant from the hole 12 through the draw-plate to give leverage to the frictional resistance to the rotation of the locking-device or washer. The 75 preferred size of the hole 14 through the washer is such that the end of the tooth will pass easily through it but without unnecessary looseness. The threaded part of the extension of the tooth preferably has the 80 shape and location which is represented in Fig. 14 when it has entered the hole in the draw-plate and is in an un-sprung condition. It will be observed in Fig. 14: that the extension of the tooth 10 fits fairly well 85 in the hole 12 of the draw-plate 6; that the extension rests in the depression 13 of the washer at its point that is radially farthest from the hole 12; but that the extension does not yet bear upon the washer in the vicinity 90 of the holes 12 and 14. The tightening of the nut 16 will spring the extension into the position that is shown in Figs. 1, 2, 3, 4, 5, 6 and 12 and into the corresponding positions that are shown in Figs. 7, 8, and 12. When 95 the locking device or washer 11 is cast or is made of sheet-metal, I prefer to make the depression or groove 13 therein of V-shaped cross-section in order to assure that the extension shall fit well therein without the 100 expense of fitting the groove to the extension. When the nut has been tightened and the extension sprung into permanent position, the tooth, the washer, and the draw-plate will be effectually locked together. 105 The springing of the extension, as has been hereinabove described, is not essential to my invention but it is in some cases preferred by me as has been hereinbefore stated.

In Fig. 12 is represented a form of locking-device from which the part that contains the hole 14 has been omitted and when 110 the pressure of the extension against the locking-device is sufficient, the tooth will be found to be effectually locked against change of direction with respect to the draw-plate. I prefer to attach the tooth to the draw-plate; partly, because the calender-roll, which is opposed to the tooth in 115 its action upon the cotton that passes between them, is a solid and substantial roll and is well adapted to oppose the forceful pressure of the tooth; partly, because the front end of the draw-plate approaches near to the bite of the calender-rolls and for this 120 reason effective teeth can be made quite short; partly, because the end-surface of the tooth can be brought very near to the bite of the calender-rolls and fibers that are 125 displaced by the tooth can almost immedi- 130

ately afterward be so bent that they will better retain their new positions; and, partly, because the trough of which the draw-plate is the bottom is open and conveniently placed and therefore the teeth can be easily reached.

Such teeth as I have herein described with the described means for their attachment are new articles of manufacture. They can be manufactured very easily and inexpensively. They can for a trivial sum be furnished to users of condenser-lap machines who are at a considerable distance from any well-equipped machine shop and they can be attached to such machines by the aid of mechanics who have no great degree of skill. When they have thus been attached, they will greatly increase the efficiency of the condenser-lap machines to which they have been applied.

I prefer to apply my hereinbefore described invention for preventing the splitting of laps to every breaker, intermediate, and finisher lapper. If the lap splits when unrolling in an intermediate or a finisher lapper or in a carding-engine, the split-off portion adheres to the outer surface of the next inner coil of the lap. The operator must, as soon as possible and as far as he can, rectify this defect in the unwinding. Otherwise, the splitting and the adhesion may continue, while the splitting lap makes several rotations about its own axis. The split may tear through the sheet. It may tear across the width of the sheet. By my invention the operative is relieved from the necessity of closely watching the unrolling laps, from the work of rectifying as far as he can the defects due to splitting, and from throwing parts of the split laps into the waste to be worked over, and the waste is prevented. In other words, the cost of production is diminished by the use of my invention. The transference of a split-off portion of the lap from the part of the sheet where it belongs to a different part of the sheet tends to non-uniformity in the weight per unit of length of the product from the machine. In the usual intermediate and in the usual finisher lapper an evener is provided and the evener tends to correct such non-uniformity, but it will not perfectly correct it. In the usual carding-engine there is no evener mechanism and the resulting non-uniformity of the product is more serious. When my invention is used the laps do not split and non-uniformity consequent upon lap-splitting does not occur.

60 I claim:

1. In means for obviating the tendency of a fibrous lap to split in machines having coacting fiber-advancing surfaces, in combination, a support located near such surfaces and having a plurality of holes there-

through, a plurality of fiber-rearranging wire teeth located in the path of the fibers, and means for attaching the teeth to the support, each of the teeth being separate and independent and each attaching means 70 consisting of an integral extension of a tooth having a threaded part adapted to pass through a hole in a washer and a hole in the support and having a portion at an angle with the threaded part adapted to be 75 drawn by a nut against the washer, a washer having a hole therethrough, and a nut for the threaded part.

2. In means for obviating the tendency of a fibrous lap to split in machines having a 80 pair of calender-rolls, in combination, a draw-plate located near such rolls and having a plurality of holes therethrough, a plurality of fiber-rearranging wire teeth located in the path of the fibers, and means 85 for attaching the teeth to the draw-plate, each of the teeth being separate and independent and each attaching means consisting of an integral extension of a tooth having a threaded part adapted to pass through 90 a hole in a washer and a hole in the draw-plate and having a portion at an angle with the threaded part adapted to be drawn by a nut against the washer, a washer having a hole therethrough, and a nut for the threaded 95 part.

3. In means for obviating the tendency of a fibrous lap to split in machines having coacting fiber-advancing surfaces, in combination, a support located near such surfaces 100 and having a plurality of holes therethrough, a plurality of fiber-rearranging spring-wire teeth located in the path of the fibers, and means for attaching the teeth of the support, each of the teeth being separate 105 and independent and each attaching means consisting of an integral extension of a tooth having a threaded part adapted to pass through a hole in a washer and a hole in the support and having a portion at an angle with the threaded part adapted to be 110 drawn by a nut into a groove in the washer, a washer having a hole therethrough and having a V-shaped groove radiating from the hole and having feet for contact with 115 the support, and a nut for the threaded part.

4. In means for obviating the tendency of a fibrous lap to split in machines having a pair of calender-rolls, in combination, a draw-plate located near such rolls and having a plurality of holes therethrough, a plurality of fiber-rearranging spring-wire teeth located in the path of the fibers, and means for attaching the teeth to the draw-plate, each of the teeth being separate and independent and each attaching means consisting of an integral extension of a tooth having a threaded part adapted to pass through 120 a hole in a washer and a hole in the draw-plate and having a portion at an angle with 125 the threaded part.

65

the threaded part adapted to be drawn by
a nut into a groove in the washer, a washer
having a hole therethrough and having a
V-shaped groove radiating from the hole
and having feet radially distant from the
hole for contact with the draw-plate, and a
nut for the threaded part.

In testimony whereof, I affix my signature
in the presence of two witnesses.
